200,980

PASTE SPREADER

Robert F. Bateman, 14 Beechcroft St., Brighton, Mass.,
and John P. Capezzuto, 350 Windsor St., Cambridge, Mass.

Filed May 9, 1963, Ser. No. 74,821

Term of patent 14 years

(Cl. D58—26)

FIG. 1 is a perspective view from the top of a paste spreader showing our new design; and
FIG. 2 is a bottom perspective view.

The opposite side of the paste spreader shown in FIG. 1 is the same as the side shown.

We claim:

The ornamental design for a paste spreader, substantially as shown and described.
